Patented Nov. 20, 1900.

E. T. MUIR.

SIDE SECTION OF CORSETS.

(Application filed Sept. 1, 1900.)

UNITED STATES PATENT OFFICE.

ERWIN T. MUIR, OF ELGIN, ILLINOIS.

DESIGN FOR A SIDE SECTION OF CORSETS.

SPECIFICATION forming part of Design No. 33,606, dated November 20, 1900.

Application filed September 1, 1900. Serial No. 28,848. Term of patent 7 years.

To all whom it may concern:

Be it known that I, ERWIN T. MUIR, a citizen of the United States, residing at Elgin, in the county of Kane and State of Illinois, have ⁵ invented a certain new and original Design for a Side Section of a Corset, of which the following, in connection with the accompanying drawings, is a full, clear, and exact specification.

¹⁰ In the said drawings, Figure 1 is a perspective view of a side section of a corset embodying my design. Fig. 2 is a plan view thereof. Fig. 3 is a plan view of the reverse side to that presented in Fig. 2; and Fig. 4 is an enlarged ¹⁵ transverse section taken on the line 44, Fig. 2.

The leading features of my design consist of the short strips A B, arranged one on each side of the continuous strip C. The short strips A extend from one end of the corset-

section to within a short distance of the other ²⁰ end, and the latter ends of said strips are provided with transverse marginal pieces or bindings D, while the continuous strip C extends beyond the marginal pieces D from one end of the section to the other. The reverse side ²⁵ of the corset-section, as presented in Fig. 3, is plain, save for the longitudinal strips or lines of stitching C', which extend throughout the length of the section.

Having thus described my invention, what ³⁰ I claim as new therein, and desire to secure by Letters Patent, is—

The design for a side section of a corset substantially as herein shown and described.

ERWIN T. MUIR.
